UNITED STATES PATENT OFFICE.

ELI B. BARRETT, OF LEONARD, TEXAS.

MOTOR-VEHICLE HEATER.

1,306,876.

Specification of Letters Patent. Patented June 17, 1919.

Application filed January 5, 1918. Serial No. 210,448.

To all whom it may concern:

Be it known that I, ELI B. BARRETT, a citizen of the United States, residing at Leonard, in the county of Fannin and State of Texas, have invented certain new and useful Improvements in Motor-Vehicle Heaters, of which the following is a specification.

This invention relates to new and useful improvements in heaters for motor vehicles. It is proposed to convey the exhaust gases from the muffler to a container capable of inflation and to inflate said container whereby a heating or warming element for the passengers of the car is provided. The exhaust gases after inflating the container pass from the same.

In carrying out the invention a flexible container is connected with the muffler and receives the warm exhaust gases. The container is connected with an outlet or discharge which includes a pressure regulator which does not release said gases until the container has been inflated; acting to maintain the inflation during operation. The container may assume the form of a pillow, a lap robe or other structure.

The invention will be more readily understood from a reading of the following specification and by reference to the accompanying drawings, in which an example of the invention is illustrated; and wherein,

Figure 1 is a perspective view showing a portion of the floor of a motor car and a heating apparatus constructed in accordance with this invention, the container having the form of a pillow;

Fig. 2 is a sectional view of the same;

Fig. 3 is a view similar to Fig. 1 showing the container in the form of a lap robe, and Fig. 4 is a sectional view of the same.

In the drawings the numeral 1 designates the floor of an automobile under which the usual muffler 2 is suitably supported. In applying this invention a pipe 3 is connected to the exhaust muffler and carried up through the floor 1. A cut-out valve 4 is included in said pipe and may be adjusted to release the gases when it is not desired to use the heater.

The pipe terminates in a nipple 5 which enters a container 6, the latter having a contracted neck receiving said nipple and being clamped thereon by a split ring 7.

The container 6 is constructed of suitable flexible material of such a nature as to be inflatable, fire proof and capable of retaining the gases supplied to the same. When inflated it has the form of a pillow. The container should be constructed of suitable fire proof cloth which is impervious to air. At its opposite end the container also has a contracted neck portion receiving an outlet nipple 8 and being clamped thereon by a split ring 9. The nipple enters a suitable pressure regulating valve 10 which may be of any approved construction. An exhaust pipe 11 leads from this valve. The object of the valve is to obstruct the escape of the gases until the container has been inflated and to hold said container so inflated, thereby permitting only the excess to escape.

In Figs. 3 and 4 I have shown the same parts with the exception of the container 6 which in this case assumes the form of a lap robe 12. In order to prevent the walls of the lap robe from distending they are connected at intervals by rivets 13. Otherwise the parts are the same with the exception of the shape of the pipes.

It is obvious that the heated gases passing from the muffler 2 will enter the container 6 or lap robe 12, as the case may be, and inflate the same whereby these containers become heating elements. After a certain inflation and a predetermined pressure has been reached the excess gases will pass the valve 10 and escape from the pipe 11, but the container will remain inflated. The container will supply ample heat for warming purposes and in warm weather may be removed from the car and easily replaced when desired. This flexible structure will be much more comfortable than one of a rigid nature.

The foregoing description and illustration clearly express the invention, but it is to be understood that said illustration is merely an exemplification and the invention may be carried out in various other ways.

What I claim, is:

In a motor vehicle heater for passengers, the combination with the exhaust pipe from the engine, of a supply pipe leading from the exhaust pipe up through the floor of the vehicle, a flexible container adjacent the floor of the vehicle and connected at one end with the supply pipe, a controlling valve in-

cluded in the supply pipe adapted to permit of the inflation or deflation of the container, said container being inflated by the gases from the exhaust pipe, an outlet connection 5 on the opposite end of the container from the supply pipe, a discharge pipe leading from the outlet down through the floor of the vehicle, and a pressure regulator in-

cluded in the outlet pipe set to withstand the pressure of the gases to a certain degree, 10 whereby the container is inflated and to release the gases through the outlet when the pressure exceeds said degree.

In testimony whereof I affix my signature.

ELI B. BARRETT.
